(57) **CLAIM**

The ornamental design for a comfort media station, as shown and described.

DESCRIPTION

FIG. 1 is a front view of the comfort media station in accordance with the invention, the broken lines forming no part of the claimed design;

FIG. 2 is side perspective view thereof, the broken lines forming no part of the claimed design; and,

FIG. 3 is a top view of FIG. 1 taken along line 3-3, the broken lines forming no part of the claimed design.

The broken lines shown in the drawings illustrate portions of the comfort media station and environmental structures that form no part of the claimed design. The jagged lines in the drawings indicate the design has no specific length.
